UNITED STATES PATENT OFFICE.

WILLIAM SHEFF, OF NEW YORK, N. Y.

DESIGN FOR A RING.

50,762.

Specification for Design.

Patented May 8, 1917.

Application filed March 2, 1917. Serial No. 152,130. Term of patent 14 years.

To all whom it may concern:

Be it known that I, WILLIAM SHEFF, a citizen of the United States, and a resident of the city of New York, borough of Manhattan, in the county and State of New York, have invented a new, original, and ornamental Design for a Ring, of which the following is a specification.

Reference is to be had to the accompanying drawings in which—

Figure 1 is a side view of a ring constructed in accordance with the present design;

Fig. 2 is an edge view of the same.

I claim—

The ornamental design for a ring as shown.

WILLIAM SHEFF.
